WINDING MACHINE

Edward J. Abbott and Winthrop L. Perry, Wilton,
N. H., assignors to Abbott Machine Company,
Wilton, N. H., a corporation of New Hampshire

Application February 28, 1938, Serial No. 193,606

20 Claims. (Cl. 242—46.7)

This invention relates to winding machines and more particularly to the construction of spindles and the spindle-held rotary winding element, such as a package core or a sleeve or the like rotary element interposed between the spindle and the package core.

The invention has particular reference to winding machines of the type in which the spindle is provided with an arm or the like for holding it alternatively in a winding position, and in an inactive position, as for example with the winding package first in contact with a drive roll and subsequently raised away from the drive roll. Without being limited to such use, the invention is especially useful in connection with automatic traveling spindle winders, for example those disclosed in United States Reissue Patent No. 18,310 and in pending United States patent application, Serial No. 726,524, filed May 19, 1934, now Patent No. 2,177,763.

In winding machines generally, and in automatic traveling spindle winders particularly, it is desirable to prevent the package from turning in an unwinding direction while in its inactive or raised position, because such turning tends to unwind the yarn, and may cause a snarl, and in automatic winders also may interfere with the subsequent end-finding and uniting operations. In the development of this invention it has been discovered that the inevitable vibration of a winding machine is transmitted to those spindles which are in a raised or inactive position in such manner as to cause them to react on their rotary winding elements (cores or rotary core-holding sleeves) in such a way as to tend to rotate their packages. When this tendency to rotate happens to cause a rotation in the winding direction, little inconvenience follows, but more often a considerable number of inactive packages will rotate in the unwinding direction, unless some ratchet or similar means is provided to stop such rotation, and in fact in some machines having usual spindle constructions most of the inactive packages turn in the unwinding direction.

It is accordingly an object of the invention to provide a spindle construction which can be applied to winding machines to prevent the reverse turning of the inactive packages due to vibration, but which will leave the packages freely rotatable in a reverse direction for the usual manual or automatic end-finding operations. A further object of the invention is to provide an improved and simplified mechanism for detach-

ably holding the package core upon a rotary sleeve or the like associated with the spindle.

Other objects of invention and features of novelty and utility will be apparent from this specification and its drawing wherein the invention is explained by way of example.

In the drawing:

Fig. 1 is a plan view partly in section and partly broken away of a winding package core, its spindle and associated parts, and the spindle-holding arm and support therefor, the parts for convenience being shown in the active or winding position, but with the package driving roll omitted for clarity of illustration;

Figs. 2 and 3 are similar fragmentary views showing the application of the invention to modified forms of winding package cores;

Fig. 4 is a sectional view on the line 4—4 of Fig. 1.

20 Referring to Fig. 1, a spindle 11 is carried by a spindle-supporting arm 12, which is pivotally connected at 13 to a part 14 of the winding unit, in such manner that the spindle and arm can be moved about the pivot 13 from the active 25 winding position shown to a raised inactive position. The winding unit may for example be one of the winding units of the reissue patent mentioned above, the units being arranged for travel from right to left.

30 The spindle element 11 extends into a generally cylindrical spindle base element 11^a, and also through a hole in the arm 12. A single set-screw 15 threaded into the spindle base element 11^a and pressing against the end of the arm 12 interlocks all of these parts, thus providing a very 35 convenient mode of assembly and rigid holding of the spindle, its base, and the arm 12.

In the form of invention of Fig. 1, the spindle is surrounded by a rotary winding element in 40 the form of a metal sleeve 16 having outer sleeve portions 16^a and 16^b adapted to fit within the axial bore of a winding package core 18, herein shown as conical. Suitable means preferably in the form of resilient elements 31 associated with 45 the sleeve 16, and more fully described below, serve to grip the inside of the core 18, so that during winding the sleeve 16 turns with the core.

Now with the construction of winding unit, spindle and core-holding sleeve just described, if 50 the sleeve 16 were supported to turn in the usual manner on portions of the external surface of spindle 11, the vibration of the winding unit would often cause the sleeve 16 and core 18, and the package on the core, to turn in an unwinding direction when these parts were in their inactive

position. According to the present invention, however, this tendency is counteracted by providing a bearing within which the sleeve turns by contact with an internal or concave surface, that is to say, by providing an external bearing for the sleeve. With the sleeve mounted at one place on an internal bearing and at another place in an external bearing, the effects of vibration as applied to the sleeve by these bearings appear to neutralize each other. Thus instead of rotating in the unwinding direction, the sleeve does not rotate appreciably when in the inactive position. Obviously in this situation, in which in a particular machine the tendency to turn in an unwinding direction is cured by utilizing an external bearing to create a countervailing tendency, the external bearing can be made large enough to overbalance the effect of the internal bearing and cause the core to turn slightly in a winding direction. Where such tendency to turn in a winding direction is not considered disadvantageous, the sleeve can obviously be mounted altogether in external bearings. However, the widest applicability of the invention is attained by employing one internal bearing and one external bearing so proportioned that their effects on the sleeve substantially neutralize each other and vibration neither turns the sleeve in the unwinding direction nor the winding direction.

A preferred construction of the external bearing for the sleeve 16 is shown in Fig. 1 as comprising a cup-shaped portion 20 of the spindle base 11^a, containing within it a wooden or fiber bushing 21 concentric with the spindle 11 and which embraces the end portion of the sleeve 16. The core 18 is suitably recessed at 22 to receive this cup-shaped portion 20 and bushing. A suitable washer 23 may be interposed between the end face of the sleeve 16 and the end of the recess which defines the cup-shaped portion 20.

A suitable internal bearing for the other or outer end of the sleeve 16 may for example comprise the external surface of the spindle 11, the sleeve 16 carrying within it a wooden or fiber bushing 24 which turns on spindle 11 adjacent to the outer end of the spindle. Throughout the remainder of the length of the spindle, the sleeve 16 has clearance from the spindle. A headed screw 25 and washer 26 may be used to retain the sleeve 16 on the spindle.

Obviously, as suggested above, the relative lengths of the external and internal bearings for the sleeve 16 may be varied so as to compensate for vibration effects tending to produce rotation of the sleeve 16 and core 18, or when appropriate, the sleeve may be mounted so that substantially all of the bearing surface on which the sleeve runs bears the external relation to it in the manner of the bushing 21.

In the embodiments of Figs. 2 and 3, in which the reference characters corresponding to those of Fig. 1 denote similar parts, the rotary winding element whose bearings are dealt with by this invention is the winding core itself, the sleeve of Fig. 1 being omitted. Fig. 2 shows a cylindrical flanged wooden core 18^a, and Fig. 3 a cylindrical plain wooden core 18^b. The cores 18^a and 18^b each have a central axial bore of sufficient diameter to clear the spindle 11, except at a place adjacent to the outer end of the core where the bore is of reduced diameter so as to provide a surface 24^a having an easy running fit with the spindle 11.

The end face of the core adjacent to the spin-

5 dle base is provided with an annular recess 22 of which the inner or convex surface 27 is concentric with the spindle and has an easy running fit with the inner cylindrical surface of the cup-shaped portion 20 of the spindle base.

10 The cores 18^a and 18^b can be retained on their spindles by any suitable latch, for example the pivoted latch shown at 29. Although the element 11 has been referred to above as the spindle, it will be apparent that in the illustrated embodiments of the invention the element designated by 11^a is also a part of what would be most conveniently termed a spindle, in the sense that it participates in rotatably supporting the rotary winding element. Accordingly, in certain 15 of the broader claims below, the term "spindle" is used in a comprehensive manner to mean the support for the rotary winding element such as the sleeve 16 of Fig. 1 or the cores 18^a or 18^b of Figs. 2 and 3.

20 In addition, while the element 11 has been shown as a separate element from the element 11, to permit the easy construction and assembly of the device, this separability is not essential in the broader aspect of the invention, and numerous advantages of the invention would be retained if elements 11 and 11^a were integral.

25 Moreover, while this specification and certain of its claims refer to an external bearing for the rotary winding element, this expression "external bearing" is not to be limited to a bearing which is altogether outside of the largest diameter of the rotary element as illustrated in Fig. 1, in the case of the rotary sleeve 16 and bushing 21, for as will be observed from Figs. 2 and 3 the external bearing exemplified by the element 29 in those figures can operate according to the same principle outside of a reduced-diameter portion of the rotary element without being totally outside the rotary element.

30 A further advantageous feature of the invention is the improved construction of parts for holding a core 18 on a sleeve such as sleeve 16, illustrated by way of example in Figs. 1 and 4. 35 As indicated above, the sleeve 16, which extends practically the full length of the core 18, is surrounded by the axially spaced outer sleeve portions 16^a and 16^b, which are preferably fast thereon. In the space between these spaced sleeves, it is preferred to insert resilient core-holding elements herein indicated by the reference numeral 31. These resilient elements are T-shaped in plan, and positioned in alternately reversed relation so that the heads of the T-shaped elements serve to space them around the periphery of the sleeve 16. The ends of the outer sleeve portions 16^a and 16^b are undercut so as to overhang at 32^a and 32^b to receive the end portions of the resilient elements, so that the two outer sleeve portions 16^a and 16^b serve to retain all of the resilient core-holding elements 31.

35 Whereas the end portions of the core-holding elements 31 are held in against the sleeve 16 by the overhanging portions 32^a and 32^b, these elements 31 are bowed outwardly except at their ends, and in the form of construction shown are provided with outwardly curved middle portions in the nature of humps 31^a. These humps together form a discontinuous peripheral enlargement 40 adapted to be received within an enlarged-diameter portion 33 of the bore of the package core. In slipping the core onto the sleeve, the elements 31 yield inwardly sufficiently to permit the core to slide over them, until the enlarged-diameter portion 33 arrives at the humped portions

31a. It will be apparent that both in applying the core to the sleeve and removing it therefrom, there is no possibility of any projecting part jamming against or injuring the core. Moreover, the ends of the T-shaped resilient elements are securely protected by the overhanging portions 32^a and 32^b, which define oppositely directed annular recesses into which the ends of the T-shaped elements extend. These resilient elements 31 are not positively fixed at either end but are slightly loose endwise, to allow the necessary endwise extension of the elements 31 as they are compressed inwardly by a core. The heads or laterally projecting portions of the T-shaped elements are curved to conform generally to the circumference of the sleeve 16, and the whole series of T-shaped elements is free to turn around the sleeve 16, when no core is on the sleeve. However, when a core is on the sleeve and is gripped by the resilient elements 31, these T-shaped elements 31 and particularly their head portions bear snugly against the sleeve 16 so that the core 18 is firmly fastened to the sleeve and the sleeve and core rotate together as a unit.

It will be apparent that the novel construction of core-holding elements can be applied to various types of textile spindles and to various types of cores.

We claim:

1. In a winding machine, a spindle for holding a rotary winding element, movable means for supporting the spindle alternatively in a winding position and in an inactive position, the spindle having one portion which defines an internal bearing and another portion which defines an external bearing for the rotary winding element, said internal bearing being of convex shape and said external bearing being of concave shape and the rotary winding element having surface portions rotatably fitting and turning in frictional contact with said bearings, whereby to minimize rotation of the winding element while the spindle is in the inactive position.

2. In a winding machine, a spindle for holding a rotary winding element, a movable spindle support engaging one end of the spindle for supporting the spindle alternatively in a winding position and in an inactive position, the spindle having adjacent to its outer end a portion which defines an internal bearing for the rotary winding element and having adjacent to the spindle support a portion which defines an external bearing for said winding element, said internal bearing being of convex shape and said external bearing being of concave shape and the rotary winding element having surface portions rotatably fitting and turning in frictional contact with said bearings.

3. In a winding machine, a spindle for holding a rotary winding element, movable means for supporting the spindle alternatively in a winding position and in an inactive position, the spindle including a portion which defines an external bearing for the rotary winding element, said external bearing being of concave shape and said rotary winding element having a surface portion rotatably fitting and turning in frictional contact with said bearing.

4. In a winding machine, a spindle for holding a rotary winding element, a movable spindle support engaging one end of the spindle for supporting the spindle alternatively in a winding position and in an inactive position, the spindle having adjacent to the spindle support a portion

which defines an external bearing for the rotary winding element, said external bearing being of concave shape and said rotary winding element having a surface portion rotatably fitting and turning in frictional contact with said bearing.

5. In a winding machine, a spindle, a rotary sleeve on the spindle adapted to hold a textile package core, a bushing interposed between the spindle and sleeve adjacent to one end of the sleeve, a second bushing surrounding the sleeve adjacent to the other end thereof, and means associated with the spindle for holding said second bushing.

15 6. In a winding machine, a spindle, a spindle base surrounding one end of the spindle, the spindle base being recessed, a rotary sleeve on the spindle adapted to hold a textile package core, the sleeve extending into the recess in the spindle base, and a bushing within said recess providing an external bearing for the sleeve.

7. In a winding machine, a spindle, a rotary sleeve on the spindle adapted to hold a textile package core, and bearing means providing an external bearing for the rotary sleeve on the spindle, said external bearing being of concave shape and the rotary sleeve having a surface portion rotatably fitting and turning in frictional contact with said bearing.

20 8. In a winding machine, a spindle, a package core thereon, and bearing means for the package core comprising a concave bearing surface concentric with the spindle, the package core having a concentric convex surface portion rotatably fitting and running in frictional contact with said concave bearing surface.

35 9. In a winding machine, a spindle, a rotary package core thereon, the core having a bore of substantially larger diameter than the spindle except adjacent to one end and there having a bore corresponding to the spindle diameter so that the spindle surface constitutes a bearing for said end of the core, the face of the opposite end of the core having an annular recess therein providing an axially concentric convex surface, and bearing means associated with the spindle 40 having an axially concentric concave surface, the said convex surface of the core rotatably fitting and turning in frictional contact with the said concave surface of the bearing means.

10. In a winding machine, a spindle, a rotary sleeve on the spindle, bearings rotatably mounting the sleeve on the spindle, the sleeve running inside of one and outside of the other of said bearings and having surface portions which fit and turn in frictional contact with said bearings, 45 and means associated with the sleeve for gripping a package core so that the sleeve partakes of the rotation of the core in winding, whereby when the winding is suspended the vibration of the spindle is prevented from imparting idle rotation to the package core.

11. In a winding machine, a spindle, a rotary sleeve on the spindle, bearings rotatably mounting the sleeve on the spindle, the sleeve running inside of one and outside of the other of said bearings and having surface portions which fit and turn in frictional contact with said bearings, 65 and a plurality of resilient elements carried by the sleeve and adapted frictionally to engage the interior of a package core to fasten the sleeve rotatably thereto.

70 12. A core holder for textile machines comprising a central member and axially spaced overhanging portions associated with said central member so as to define oppositely directed recesses adjacent to the periphery of said central

member, and resilient core-engaging elements having their end portions seated in said recesses.

13. A core holder for textile machines comprising a central member and axially spaced overhanging portions associated with said central member so as to define oppositely directed recesses adjacent to the periphery of said central member, and resilient outwardly bowed core-engaging elements having their end portions seated in said recesses.

14. A core holder for textile machines comprising a central member, a plurality of separate resilient core-engaging elements, and means for retaining said elements in association with said member, the resilient elements extending generally lengthwise of the central member and having laterally extending parts serving to space them around the periphery of the central member.

15. A core holder for textile machines comprising a central member, a plurality of resilient core-engaging elements, and means for retaining said elements in association with said member, the resilient elements being of generally T shape and being disposed in alternately reversed position so that the heads of the T's serve to space the elements around the periphery of the central member.

16. A core holder for textile machines comprising a central member, a plurality of resilient outwardly bowed core-engaging elements, and means for retaining said elements in association with said member, the resilient elements being of generally T shape and being disposed in alternately reversed position so that the heads of the T's serve to space the elements around the periphery of the central member.

17. A core holder for textile machines comprising a central member, a plurality of resilient outwardly bowed core-engaging elements, and means for retaining said elements in association with

said member, the resilient elements being of generally T shape and being disposed in alternately reversed position so that the heads of the T's serve to space the elements around the periphery of the central member, the several resilient elements having humped portions adjacent to their middles, the several humped portions together forming a discontinuous peripheral enlargement adapted to be received within and hold

10 a core.

18. A core holder for textile machines comprising a central member, a plurality of separate resilient outwardly bowed core-engaging elements, and means for retaining the ends of said elements loosely in association with said central member, said resilient elements having humped portions adjacent to their middles, said humped portions together forming a discontinuous peripheral enlargement adapted to be received within an enlarged-diameter portion of the bore of a core held by said holder.

19. A core holder for textile machines comprising a central member and axially spaced sleeve elements having end portions undercut so as to form oppositely directed annular recesses adjacent to the periphery of said central member, and resilient core-engaging elements having their end portions loosely seated in said annular recesses.

20. In a core holder for textile machines comprising a central generally cylindrical member, a plurality of separate resilient core-engaging elements, and means for retaining said elements in association with said member, the resilient elements extending generally lengthwise of the central member and having laterally extending parts curved to conform to the periphery of the central member.
